(57) **CLAIM**

The ornamental design for a suction fixture, as shown and described.

DESCRIPTION

FIG. 1 is a top plan view of a suction fixture showing my new design;

FIG. 2 is a front elevational view thereof;

FIG. 3 is a bottom plan view thereof;

FIG. 4 is a rear elevational view thereof;

FIG. 5 is a left side elevational view thereof;

FIG. 6 is a right side elevational view thereof;

FIG. 7 is a front right perspective view thereof; and,

FIG. 8 is a front left perspective view thereof in an alternate position of use.
